LAMP BULB MOUNTING

Clarence A. Michel and Howard C. Mead, Anderson, Ind., assignors to General Motors Corporation, Detroit, Mich., a corporation of Delaware

Original application March 29, 1934, Serial No. 717,886. Divided and this application January 18, 1937, Serial No. 121,046

9 Claims. (Cl. 240—41)

This is a division of our prior application Serial No. 717,886, filed March 29, 1934.

This invention has to do with arrangements for mounting bulbs in a reflector, especially bulbs with what is known as a prefocused base. A pre-focused base is a base provided with locating means such as a flange, usually in the form of a ring surrounding the body of the base and extending radially outward therefrom. The ring is secured to the body of the base in accurate relation to the bulb filaments and when the bulb is positioned in engagement with the reflector or other support the filament is accurately located with respect to the deflector.

According to the present invention the bulb is held in position by spring means preferably in the form of a contracting ring made of coiled spring wire. If desired, means may be provided to hold the bulb against rotation. The spring may serve not only to hold the bulb in place but also to hold a connector in position to supply current to the bulb.

Other details of the invention will be made clear in the course of the following description taken in connection with the accompanying drawings in which:

Figure 1 is a vertical section through one form of mounting for securing the bulb in the reflector, while Figure 2 is a rear view with the contact carrier removed.

Figure 3 is a vertical section through another modification.

Figure 4 is a section on line 4—4 of Figure 3.

Figure 5 is a rear view of the construction of Figure 3.

Figures 6, 7 and 8 are vertical sections through further modifications.

Figure 9 is a rear view of the form of the invention shown in Figure 8, with parts broken away.

Figure 10 is a vertical section through a further modification, while Figure 11 is a perspective view showing the modified form of bulb employed in Figure 10, together with the sleeve used to assist in holding the bulb in position.

In all the figures, 10 indicates a portion of the reflector, and 12 the socket for receiving the flange of the locating ring 13 of the bulb. 14 indicates the sleeve portion of the locating ring which encircles the bulb base 16, and is soldered thereto after the bulb has been properly adjusted. 18 indicates a flange extending radially outward from the ring adapted to seat in the bottom of the socket 12. The flange may be provided with lug 20 to engage in a notch, or opening in the

bottom of the socket and hold the bulb against rotation. The sleeve portion 14 is provided with a radial projection which may take the form of an annular rib 22. Reflector 10 is provided with three radially spaced hook-shaped lugs 24. Keyed over these lugs and wedged between projection 22 and the rear of the reflector is a helical spring 26 in the form of an annulus. Spring 26 is under tension, and consequently serves to push against rib 22 and draw the bulb rearwardly so that the flange 18 is held yieldingly in engagement with the bottom of the socket.

In the form of the invention shown in Figures 1 and 2 the bulb base is somewhat lengthened, and is provided with bayonet pins 28 to permit connection of the contact carrier 30 in the form of a cup through which passes conductor 32 connected to contact 34 seated on insulating disc 36 which is pressed forwardly by coil spring 38.

With this form of the invention, it will be obvious that the bulb, and contact carrier may be removed from the reflector by simply pulling the bulb forwardly, and thereafter the contact carrier may be separated from the bulb if desired.

The form of the invention shown in Figures 3 to 5 is similar to that shown in Figures 1 and 2, except that the contact carrier remains in place upon removal of the headlamp. The contact carrier 130 is in the form of a cup having a flange 48 at its open end seated in the sub-socket 50 formed within the socket 12. The carrier 130 is provided with an integral lug 54 engaging in a notch in the reflector to prevent rotation. The carrier 130 is also provided with outwardly pressed lugs 56 providing seats for the helical spring 58, and with circumferentially spaced slots 60 to permit the spring 58 to engage behind rib 22 on the locating ring of the bulb. The locating ring in this form of the invention is of the same construction as that shown in Figures 1 and 2, except that it is somewhat longer. As best shown in Figure 3 the coil spring 58 wedges between lugs 56 and the back of the reflector, and thus holds the flange 48 on the carrier 130 in engagement with the sub-socket. At the same time portions of the spring passing through slots 60 engage the rib 22 and urge the bulb into the socket 12.

In this form of the invention the bulb is shown equipped with contacts in the form of flat prongs 62 which engage return bent contacts 64 received in two part housing 66 made of insulating material and held within the carrier 130. As shown in Figure 4 the insulator 66 is provided with an outwardly extending flange 68 having the rear

surface thereof formed on a radius so as to have 5
rocking contact with the closed end of the cup- shaped carrier 130. The purpose of this arrangement is to permit the bulb to fit into the contact carrier whatever be the angular relation of the prongs to the axis of the locating ring. The provision of the rocking mounting of the insulator 66 in the carrier 130 permits adjustment in one direction, and the slots in the insulator receiving the contacts 64 are wider than 10
the prongs 62 so as to permit adjustment in a direction at right angles to the axis of rocking movement provided by the flange 68.

The modification shown in Figure 6 is substantially the same as that shown in Figures 3 to 5, 15
except that the contact housed within the contact carrier 130 is of the type previously described in connection with Figure 1.

The modification shown in Figure 7 is substantially the same as that shown in Figure 1, except 20
that the locating ring 113 on the bulb is lengthened and provided with bayonet slot connection 70 with contact carrier 72. With this construction the bulb locating ring, contact carrier, and leads will come out with the bulb.

The form of invention shown in Figures 8 30
and 9 is characterized by the fact that lugs 74 are pressed out of the side wall of the socket 12. These lugs serve to retain the annular helical spring 76 in position so that it acts to yieldingly 35
press the flange of the locating ring 213 of the bulb against the socket 12. The bulb is disengaged from the socket 12 by pulling or tilting it forwardly, causing the spring 76 to expand and release the locating ring 213. In this form of the invention the reflector is provided with a lug 78 adapted to seat in a notch 79 in the flange of the locating ring 213 to prevent rotation of the bulb in its socket. Obviously, with this construction some provision must be made to support the contact carrier, but this may be done in any of the ways previously described.

In the modification disclosed in Figures 10 and 11 the locating ring 313 has its tubular portion 45
extending forwardly as in the case of the form last described. Diametrically opposite portions of the flange of the ring are bent outwardly of the plane of the flange as at 80 and lie along the bulb base. The ends of the portions 80 are 50
formed to provide ribs to receive the encircling coil spring 82. 84 indicates a sleeve provided at its forward end with outwardly pressed lugs 86 adapted to be seated in a groove or sub-socket 88 formed in the socket 12. Sleeve 84 is also provided with outwardly pressed lugs 90, and with 55
slots 92 to accommodate the members 80. In assembling the parts as shown in Figure 10, the sleeve 84 is first inserted in the socket and the lugs 86 are then bent outwardly to prevent its removal. Coil spring 82 is then engaged over the lugs 90 so that it yieldingly holds the sleeve in the reflector. Suitable means may be provided to prevent relative rotation of the parts. In inserting the bulb, it is but necessary to position it so that the lugs 80 enter the slots 92, and thereafter the ribs on the member 80 snap behind the spring 82 and the bulb is clamped tightly in position.

We claim:

1. The combination of a support having an 70
apertured portion, a bulb having a base extending into the aperture in the support and provided with a radially extending portion adapted to engage one side of the support, a contact carrier 75
provided with contacts for engagement with the

contacts on the base, spring means cooperating with the support, bulb base and contact carrier to hold the bulb yieldingly to the support and the contact carrier in yielding engagement with the base, and cooperating means on the bulb base and support for preventing rotation of the bulb with respect to the support. 5

2. In the combination as defined in claim 1, said spring means comprising a contracting spring ring. 10

3. The combination of a support having an apertured portion, a bulb having a base extending into the aperture in the support and provided with a radial projection adapted to engage one side of the support, and with a radial projection at the rear of the support, a contact carrier having portions straddling the base, and spring means encircling the contact carrier and base and engaging the rear of the support and the last named projection so as to exert yielding pressure on the bulb to hold it in position with the contact carrier in operative relation thereto. 15

4. In combination: an incandescent electric lamp; a mounting for said lamp; said lamp having a base provided with lamp contact means; said base having lateral extension means a first portion of which abuts said mounting; carrier means, carrying contact means cooperable with said lamp contact means; and means, including a second portion of said lateral extension means, and including a portion of said carrier, constructed and arranged to detachably connect said carrier and said base so that said carrier means is supported solely by said base. 30

5. In combination: an incandescent electric lamp; a mounting for said lamp; said lamp having a base provided with lamp contact means; said base having lateral extension means a first portion of which abuts said mounting; carrier means, carrying contact means cooperable with said lamp contact means; and means, including a second portion of said lateral extension means, disposed radially inwardly of said first portion, and including a portion of said carrier, constructed and arranged to detachably connect said carrier and said base so that said carrier means is supported solely by said base. 45

6. The combination of a support having an apertured seat, a tubular contact carrier fitted in said aperture and having a radial projection engaging said seat to position the contact carrier therein, a bulb having a base adapted to be inserted in said tubular contact carrier provided with a radial projection positioning the bulb with respect to the seat, and common means cooperating with the contact carrier, bulb and support yieldingly holding said carrier and bulb in position in said seat. 50

7. In the combination as defined in claim 6, 60
said seat comprising axially stepped portions, the projection on said carrier engaging the stepped portion nearer the axis while the projection on said base engages the stepped portion further from the axis. 65

8. The combination of a support having an apertured seat, a tubular contact carrier fitted in said aperture and having a radial projection engaging said seat to position the contact carrier therein, a bulb having a base adapted to be inserted in said tubular contact carrier provided with a radial projection positioning the bulb with respect to the seat, said contact carrier and bulb base having radial projections located at the rear of said support when said carrier 70
75

and bulb are in operative position therein, and resilient means engaging said last-named projections and the support yieldingly holding said contact carrier and bulb in position in said seat.

9. The combination of a support having an apertured seat, a tubular contact carrier fitted in said aperture and having a radial projection engaging said seat to position the contact carrier therein, a bulb having a base adapted to be inserted in said tubular contact carrier provided with a radial projection positioning the bulb with

respect to the seat, said contact carrier and bulb base having radial projections located at the rear of said support when said carrier and bulb are in operative position therein, said carrier having a slot therein to expose the rear projection on said bulb base, and yieldable means encircling said carrier and base and engaging said last-named projections and support and yieldably holding said contact carrier and bulb in position in said seat.
